Primary Examiner — Mark A Goodwin(57) **CLAIM**

The ornamental design for a peg as shown and described.

DESCRIPTION

FIG. 1 is a perspective view of the peg;
FIG. 2 is a front elevational view of the peg, where the rear elevational view is symmetrical;
FIG. 3 is a side elevational view of the peg, where the opposite side elevational view is symmetrical;
FIG. 4 is a bottom plan view of the peg; and,
FIG. 5 is a top plan view of the peg.
Broken lines appearing in the drawings are intended to be for illustrative purposes only and form no part of the claimed design.

1 Claim, 5 Drawing Sheets(56)
